ATTORNEY.

UNITED STATES PATENT OFFICE

CLYDE S. WRIGHT, OF TOLEDO, OHIO, ASSIGNEE TO THE WRIGHT
OF TOLEDO, OHIO, A CORPORATION OF OHIO

WELL-DRILLING APPARATUS

Application filed May 27, 1927. Serial No. 194,552

My invention relates to well-drilling apparatus.

One object of this invention is to provide a portable well-drilling apparatus which may, if desired, be attached to a mast or a tower erected at a well. Another object is to provide novel details of construction which will be explained and claimed hereinafter.

Referring to the accompanying drawings,
10 Fig. 1 is a side elevation of a drilling apparatus containing my invention, a portion being broken away; Fig. 2, an enlarged side elevation of that part of my apparatus in which the invention particularly resides; Fig. 15 3, an elevation like that of Fig. 2, but showing the side opposite; and Fig. 4, an elevation looking at Fig. 2 from the left.

On the drawings, 1 designates a mast in elevated position. It has the foot 2 resting on the base 3 and suitable sheaves at the top (only one, marked 4, being shown) for the tool line 5 and the line 6 which may be attached, as shown in Fig. 1, to the tool line by the clamp 7 in a manner and for purposes well known. When the line 6 is connected to the tool line 5 by the clamp 7, that part of the tool line below the clamp becomes an extension of the line 6. In fact, the line 6, and the line 5 from the clamp down constitute the drill line. The line 5 is connected to the hoist drum 8 on the tractor 9.

35 The lower end of the mast has at opposite sides thereof the two channel bars or braces 10 which diverge downwardly and have their upper ends in engagement with the mast and connected together by the gusset plates 11 engaging opposite sides of the mast and riveted to opposite edges of the bars 10. The lower ends of the bars 10 are connected together by 40 the base channel bars 12 which engage opposite sides of the mast and are riveted to the said bars. A channel bar 13 parallel with the base bars 12 is riveted to the rear edges of the bars 10.

45 The parts so far described may be a permanent feature, the parts 10, 11, 12 and 13 comprising a frame to which a pulling mechanism of the general type shown in my application Serial No. 185,984 filed April 23, 1927 may be removably attached. To this frame the

1927. Serial No. 194,592.
A portable drilling or spudding device now to be described may be removably attached, as desired, to a derrick or other structure suitable to

The frame of the spudding or drilling device comprises the two side members 14 and 15 spaced apart by the transverse or end members 16 which are clamped between the side members by the bolts 17. The said frame is detachably connected to the aforesaid frame on the mast by the bolts 18 and 19, the bolt 18 extending through the upper end frame member 16 and one of the bars 10, the gusset plates 11, and a spacing block 20 between the side frame member 14 and the gusset plates 11.

The bolts 19 extend through the base bars 12, the mast 1, the lower end of the side frame member 14, and the spacing block 21 seated between the said member 14 and the adjacent base bar 12. The side frame member 15 is connected to the base bars 10 by the bolts 22. 70

The side members 14 and 15 of the frame just described support the bars 23 parallel therewith and carrying at their upper and lower portions the bearings 24 and 25 for the horizontal shafts 26 and 27. The shaft 75 27 is the driving shaft and carries the sprocket wheel 28 driven by the tractor through appropriate driving means, as shown. The shaft 27 carries also the pinion 29 which drives the spur gear 30 on the shaft 26, which 80 has keyed thereto the crank arm 31.

32 is a lever having one end connected by the pivot 33 to the bracket 34 which is secured to the bar 13 by the bolt 35. The lever has the slot 36 extending longitudinally thereof to receive the crank-pin 37 carried by the crank arm 31. The line 6 is connected to the free or outer end of the lever 32, which in its middle position is horizontal.

With the parts as in Figs. 1 and 2 and the crank arm and gear rotating in the direction shown by the arrow on Fig. 2, the arm will be forced down at a comparatively slow speed since the crank pin is at its maximum distance from the pivot 33 of the lever. This provides a slow speed for raising the drilling tools on the lower end of the line 5.

When the crank pin is traveling up between the shaft 26 and the pivot 33 the lever evidently has a faster movement upwardly than

it had downwardly. The tools are lifted at first from rest very slowly, their speed upwardly increasing gradually from the travel of the lever from its upper position shown in Fig. 3 to its medial position shown in Fig. 5 in Fig. 3 to its medial position shown in Fig. 5. The tools will begin to drop rapidly as soon as the crank arm starts upwardly.

38 are braces between the side frame members 14 and 15.

10 I claim—

In a well drilling apparatus, a mast, a frame comprising a parallel pair of base bars at opposite sides of the lower end of the mast, a pair of brace bars secured to opposite ends of the base bars and inclined upwardly to engage opposite sides of the mast, and a pair of plates engaging the opposite sides of the mast and secured to the opposite sides of the upper ends of the brace bars, in combination 15 with a machine frame, a mechanism mounted on the machine frame and adapted to cooperate with the mast, and means for detachably connecting the frames together.

In testimony whereof, I hereunto affix my 25 signature.

CLYDE S. WRIGHT.
